UNITED STATES PATENT OFFICE.

JAMES WILLIAM GARDNER, OF JARRATT, VIRGINIA, ASSIGNOR TO
L. L. POND AND W. T. POND, OF PINOPOLIS, VIRGINIA.

HARNESS-SADDLE.

No. 815,917.

Specification of Letters Patent. Patented March 20, 1906.

Application filed September 6, 1905. Serial No. 277,186.

To all whom it may concern:

Be it known that I, JAMES WILLIAM GARDNER, a citizen of the United States, residing at Jarratt, in the county of Sussex and State 5 of Virginia, have invented certain new and useful Improvements in Harness-Saddles; and I do hereby declare the following to be a full, clear, and exact description of the invention, such as will enable others skilled in the 10 art to which it appertains to make and use the same.

My invention relates to harness, and more particularly to an attachment for a harness-saddle whereby the traces of the harness will 15 be held out of contact with the body of the horse, thereby rendering the device particularly adapted for use in plowing or in drawing heavy loads.

One of the great objections which have 20 been experienced by farmers has been the side motion given to the plow by the traces coming in contact with the sides of the horse's body. As a result considerable effort is required to keep the plow traveling in a straight 25 line, and at the same time the horse's body is often injured because of the rubbing which is produced.

The object of my invention is to provide 30 means of simple construction which is mounted upon the saddle of the harness and which stands some distance beyond the sides of the horse, where it engages the traces and holds them out of contact with the horse's body.

A still further object is to provide an attachment of this character which can be adjusted so as to render the same capable of moving upon the saddle or of remaining permanently connected thereto.

With the above and other objects in view 40 the invention consists of certain novel features of construction and combination of parts, which will be hereinafter more fully described, and pointed out in the claims.

In the accompanying drawings I have 45 shown the preferred form of my invention.

In said drawings, Figure 1 is a perspective view of a saddle having my improved attachment thereon, a portion of one of the traces being shown connected thereto. Fig. 2 is a 50 longitudinal section through the saddle and showing the central portion of the yoke therein, and Fig. 3 is a detail view of one end of one of the yoke-sections.

Referring to the figures by numerals of ref-

erence, 1 1 are the members of a saddle, the 55 same being connected by a flexible strip 2. Each member has a bracket 3 secured upon it, in which is mounted a roller 4. The two rollers constitute supports for a yoke consisting of similar oppositely-disposed members 5 60 and 6, each of said members being provided with a series of apertures 7 and having at its free end a laterally-extending lug 8, adapted to fit within any of the apertures of the other member. The two members of the yoke 65 curve downward to form tapered arms 9, having hooks 10, which are adapted to engage the traces 11 of a harness. A bolt 12 is adapted to be placed within registering apertures of the members 5 and 6, so as to secure them in adjusted position.

Where a device such as herein described is employed, the arms 9 of the yoke will extend to the sides of the horse at some distance therefrom, and when the traces are engaged thereby they will be held out of contact with the horse's body and will not, therefore, rub it or be moved from side to side by the lateral movement of the horse's body. Moreover, the yoke is capable of moving longitudinally upon the rollers 4, so as to further reduce or obviate the side movement of the traces. The arms can be adjusted from or toward each other by removing the bolt 12 and placing the lugs 8 into any of the apertures 7, after which the two members of the yoke can be again clamped together by means of the single bolt 12. Should it be desired to prevent longitudinal movement of the yoke upon the saddle, the pivot-bolts 13 of the 80 rollers 4 can be removed and instead extended into apertures 7, so as to secure the yoke 85 rigidly to the saddle.

It will be seen that this device is very desirable for use in plowing or wherever a horse 95 is required to pull a heavy load, and the entire yoke can be made of very light metal, and the attachment can be readily applied to harness ordinarily used.

Having thus fully described my invention, 100 what I claim as new, and desire to secure by Letters Patent, is—

1. The combination with a harness-saddle; of brackets secured thereto and a longitudinally-extensible rigid yoke movably mounted within and extending through the brackets and adapted to engage the traces of harness.

2. The combination with a harness-saddle having brackets thereon; of a longitudinally-extensible rigid yoke projecting through the brackets and adapted to engage the traces of the harness.
5. The combination with a harness-saddle having brackets thereon; of a longitudinally-extensible rigid yoke slidably mounted within and extending through the brackets and adapted to engage the traces of the harness, and means for rigidly securing the yoke in extended position.
10. The combination with a harness-saddle having brackets thereon; of a rigid yoke mounted within the brackets and adapted to engage the traces of a harness, said yoke comprising oppositely-disposed, similar members adjustably connected to extend or shorten
- 15.

the yoke, and means for securing said sections in adjusted position.

5. The combination with a harness-saddle having brackets thereon; of a yoke mounted within the brackets and adapted to engage the traces of a harness, said yoke comprising oppositely-disposed similar apertured members having overlapping ends, means upon said ends for engaging the opposite members, and a clamping device for securing the members together.

In testimony whereof I have signed my name to this specification in the presence of two subscribing witnesses.

JAMES WILLIAM GARDNER.
